CLAIM

The ornamental design for a vehicle exterior, as shown and described.

DESCRIPTION

FIG. 1 is a front-right corner perspective view of a vehicle exterior showing the claimed design;

FIG. 2 is a front-left corner perspective view of the vehicle exterior;

FIG. 3 is a left-side view of the vehicle exterior;

FIG. 4 is a right-side view of the vehicle exterior;

FIG. 5 is a top view of the vehicle exterior;

FIG. 6 is a rear view of the vehicle exterior; and,

FIG. 7 is a rear-right corner perspective view of the vehicle exterior; and,

FIG. 8 is a rear-left corner perspective view of the vehicle exterior.

The dashed broken lines represent boundaries of the design; the dashed broken lines themselves and the areas within form no part of the claimed design.

1 Claim, 8 Drawing Sheets

US D1,008,100 S
